UNITED STATES PATENT OFFICE.

JOSEPH E. HEASLEY, OF BUTLER, PENNSYLVANIA.

COMBINATION CLOTHES-LINE AND CLOTHES-PIN CONSTRUCTION.

1,211,312.

Specification of Letters Patent. Patented Jan. 2, 1917.

Application filed June 17, 1915. Serial No. 34,594.

To all whom it may concern:

Be it known that I, JOSEPH E. HEASLEY, a citizen of the United States, residing at Butler, in the county of Butler and State of Pennsylvania, have invented certain new and useful Improvements in Combination Clothes-Line and Clothes-Pin Constructions, of which the following is a specification.

The present invention relates to a combination wire clothes line and clothes pin, and has for its object to provide a device of this character which embodies novel features of construction whereby the clothes pins may be applied to the clothes line at convenient points in the length thereof and caused to engage and disengage the clothes without the necessity of removing the clothes pins from the clothes line.

Further objects of the invention are to provide a device of this character which is comparatively simple and inexpensive in its construction, which will enable clothes to be suspended from the clothes line or removed therefrom without the inconvenience of attaching and detaching a large number of clothes pins which must ordinarily be supplied one at a time when hanging the clothes and collected one at a time when removing the clothes from the line, which will enable the clothes to be suspended without danger of being torn or injured, and which will result in the saving of much time in handling the clothes.

With these and other objects in view, the invention consists in certain novel combinations and arrangements of the parts as will more fully appear as the description proceeds, the novel features thereof being pointed out in the appended claims.

For a full understanding of the invention, reference is to be had to the following description and accompanying drawing, in which:

Figure 1 is a front elevation of a clothes line constructed in accordance with the invention, showing the manner of applying the clothes pins thereto, and the manner of applying the clothes to the clothes pins. Fig. 2 is a transverse sectional view taken 50 on the line 2—2 of Fig. 1.

Corresponding and like parts are referred to in the following description and indicated

in all the views of the drawing by the same reference characters.

Specifically describing the present embodiment of the invention, the numeral 1 designates a clothes line which is preferably formed of wire, and which is provided at convenient intervals in the length thereof with eyes 2. These eyes may be formed in any suitable manner, although they are preferably constructed by making small coils in the wire.

A special clothes pin 3 is employed in connection with the clothes line and is constructed in such a manner that it can be quickly applied to any selected one of the eyes 2 in such a manner as to be suspended therefrom. The clothes pin 3 is formed from a length of spring wire which is bent into a substantially U-shaped formation, the two arms of the clothes pin being deflected inwardly at intermediate points in their length to provide opposed jaws 3^a between which the clothes are adapted to be gripped and the free ends of the arms being deflected outwardly at 3^b to provide a flared mouth leading to the jaws 3^a. When the clothes pins 3 are applied to the eyes 2 of the line 1, the jaws 3^a can be readily swung apart an amount sufficient to admit of the eyes passing into the looped upper end of the clothes pin so that the clothes pins will hang freely from the eyes. The clothes pins 3 can thus be applied to the clothes line 1 at suitable intervals, and in order to suspend clothes from the line it is merely necessary to draw portions thereof forcibly between the jaws 3^a of the clothes pins. This avoids the necessity of carrying a number of clothes pins in the hand and supplying them one at the time as needed when hanging the clothes, and also of collecting the clothes pins when collecting the clothes. Much time and annoyance is thus saved and the clothes pins can either be permitted to remain permanently upon the clothes line or detached therefrom, as may be found most desirable.

Under ordinary conditions they would remain permanently upon the clothes line and the positions thereof upon the clothes line shifted as found necessary. In order to apply the clothes to the clothes line portions thereof are merely inserted in the flared

mouths of the pins and drawn forcibly between the spring jaws thereof, while in order to remove the clothes it is merely necessary to forcibly disengage them from the 5 jaws of the clothes pins.

Having thus described the invention, what I claim as new and desire to secure by Letters Patent, is:—

As a new article of manufacture, the here-
10 in described wire clothes line formed of a single strand of wire which is provided at

periodic intervals with spiral coils providing suspending eyes, any selected ones of the suspending eyes being adapted to interlock with and support clothes pins. 15

In testimony whereof I affix my signature in the presence of two witnesses.

JOSEPH E. HEASLEY.
